UNITED STATES PATENT OFFICE

161,820

ARTIFICIAL FISHING LURE

Charles E. Brooks, Nashville, Tenn.

Application September 9, 1949, Serial No. 4,918

Term of patent 14 years

(Cl. D31—4)

To all whom it may concern:

Be it known that I, Charles E. Brooks, a citizen of the United States, residing at Nashville, in the county of Davidson and State of Tennessee, have invented a new, original, and ornamental Design for an Artificial Fishing Lure, of which the following is a specification, reference being had to the accompanying drawings, forming a part thereof.

Figure 1 is a front elevational view of an artificial fishing lure, showing my new design;

Figure 2 is a top plan view;

Figure 3 is a side elevational view;

Figure 4 is a bottom plan view.

I claim:

The ornamental design for an artificial fishing lure, as shown.

CHARLES E. BROOKS.
